DESIGN FOR A FITTING TABLE

Arne J. Oker, Southbridge, Mass., assignor to
American Optical Company, Southbridge, Mass.,
a voluntary association of Massachusetts

Application March 24, 1938, Serial No. 76,061

Term of patent 14 years

To all whom it may concern:

Be it known that I, Arne J. Oker, a citizen of the United States of America, residing at Southbridge, in the county of Worcester and State of Massachusetts, have invented a new, original, and ornamental Design for a Fitting Table, of which the following is a specification, reference being made to the accompanying drawing, forming a part thereof.

Fig. I is a front perspective view of a fitting table embodying my design; and

Fig. II is an end view of the table shown in Fig. I.

Fig. III is a rear perspective view of the table shown in Fig. I and II, on a reduced scale.

The dominant features of the design reside in the provision of a main table-like top having depending box-like portions adjacent the opposed ends thereof supported by a skeleton-like frame of bar material substantially as shown in the drawing. The front of said box-like portions is provided with bar-like ornaments as shown.

I claim:

The ornamental design for a fitting table, substantially as shown and described.

ARNE J. OKER.
